POSTER PANEL WITH RAISING AND LOWERING MEANS

Alexander L. Bauers, Chicago, Ill., assignor to General Outdoor Advertising Co., Inc., Chicago, Ill., a corporation of New Jersey

Application January 12, 1946, Serial No. 640,935

9 Claims. (Cl. 40—125)

1. This invention relates to poster panels and

more particularly to poster panels having a supporting structure and a display panel which may be moved between a raised display position and a lowered service position.

The principal object of this invention is to provide improved means for guiding the display panel as it is moved between the raised display position and the lowered service position. In this respect, guide tracks and guide rollers are utilized so that the display panel may be moved and guided with the least amount of friction and a guided counterweight is also utilized to balance the weight of the display panel. With this arrangement one man may readily move the display panel between its display and service positions.

A further object of this invention is to provide the guide tracks with inclined portions which cooperate with the guide rollers to move the display panel against the border frame of the supporting structure in display position and to move the display panel forward of the border frame when it is lowered to the service position. In this way the display panel is rigidly supported in display position but may be readily lowered to service position.

Further objects of the invention reside in the details of construction of the guide track and guide roller mechanisms.

Other objects and advantages will become apparent to those skilled in the art upon reference to the accompanying specification, claims and drawing in which:

Fig. 1 is a front elevational view of a poster panel forming this invention;

Fig. 2 is a rear elevational view thereof;

Fig. 3 is an enlarged vertical sectional view through the poster panel;

Fig. 4 is an enlarged partial rear view of the poster panel;

Fig. 5 is an enlarged partial sectional view showing the details of the lower guide roll assembly when the display panel is in the display position;

Fig. 6 is a view similar to Fig. 5 with the parts in position when the display panel is lowered to service position; and

Fig. 7 is an enlarged sectional view taken substantially along the line 7—7 of Fig. 3.

The poster panel is generally designated at 10 and it includes a supporting structure comprising horizontal supporting braces 11, 12 and 13 adapted to be fastened to any desired mounting structure, not shown. A border frame 14, preferably made of sheet metal, is secured to the

2

horizontal braces 11, 12 and 13. A base member 14' also preferably made of sheet metal is suitably secured to the border frame 14. A display panel 15 is supported by the supporting structure and is adapted to be moved to a display position as shown in Figs. 1 and 3, and to be moved to a lowered service position as shown in dotted lines in Fig. 3.

In order to guide the display panel 15 for movement between the raised display position and the lowered service position, the supporting structure includes a pair of vertically arranged guide tracks 16 secured to the horizontal braces 11 and 12, and a pair of vertically arranged guide tracks 17 secured to the back of the display panel 15. A counterbalance weight 18 is utilized for balancing the weight of the display panel 15.

In order to reinforce and make more rigid the border frame 14, it is provided with flanges 20 around the periphery thereof. Adjacent the opening in the border frame 14 it is provided with abutting surfaces 21 for receiving the display panel 15 in abutting relation. A guard 22 is formed on the upper portion of the border frame to prevent moisture from entering between the border frame 14 and the display panel 15. The upper abutting surface 21 may be suitably secured to the border frame under the guard 22.

30 The display panel 15 is preferably a fabricated sheet metal panel having internal braces 24 and external braces 25 and 26.

Mounted on the upper horizontal brace 11 and interposed between the brace 11 and the border frame 14 are a pair of sheave housings 28, each rotatably carrying a sheave 29. One end of each of a pair of cables 30 is attached to the brace 26 of the display panel 15 and the cables extend over the sheaves 29 and are secured to the counterweight 18. The counterweight 18 is provided with a pair of eyes 31 which accommodate a pair of cables 32 secured between the horizontal braces 11 and 12. The cables 32 may be maintained taut by turnbuckles 33. The cables 32 act to guide

45 the movement of the counterweight 18 which, in turn is connected through the cables 30 to the display panel 15. As the display panel 15 is moved upwardly and downwardly, the counterweight 18 moves downwardly and upwardly for the purpose of counter-balancing the weight of the display panel 15. Utilizing the cable guides 32 and the sheave assemblies 29, as illustrated, makes possible counterbalancing of the weight of the display panel 15 with the least amount of friction.

50 The guide tracks 16 are each of double channel

form, as illustrated in Fig. 7. The guide tracks 16 are inclined at their upper ends, as shown at 36, and the upper ends of the guide tracks 16 are secured to the horizontal brace 11 by straps 37. The lower ends of the guide tracks 16 are secured by straps 38 to the horizontal brace 12.

A compound guide roller 40 is located within the double channel guide track 16 for rolling operation therein and is connected by a bracket 41 to the external brace 25 of the display panel 15. Therefore, as the display panel 15 is raised or lowered, the upper portion thereof is guided by the roller 40 operating in the double channel track guide 16. As the display panel is moved upwardly and downwardly and the roller 40 is operating in the inclined portion 36 of the track guide 16, the upper portion of the display panel 15 is moved toward and away from the border frame 14.

The track guides 17, carried by the rear of the display panel 15, are provided with inclined surfaces or cam surfaces 43 adjacent the lower ends thereof. Rollers 44 roll in the track guides 17 and are carried by arms 45 pivoted at 47 to brackets 46 secured to the horizontal brace 12.

The display panel 15 may be provided with a suitable latch and handle 48 for latching the display panel 15 in the display position, as shown in Fig. 3.

When the display panel 15 is in the upper display position, as illustrated in Figs. 3 and 5, the rollers 40 are in the upper portions of the inclined portions 36 of the guide tracks 16 and the pivoted arms 45 carrying the guide rollers 44 are in the retracted position. As a result the display panel 15 is abutting the surfaces 21 of the border frame 14 and the display panel 15 may be held in this position by the latch member 48. The display panel 15 is, therefore, rigidly secured to the supporting structure.

When it is desired to lower the display panel 15 from the display position to the service position, the latch member 48 is operated and the lower end of the display panel 15 swung forwardly. This permits the pivoted arms 45 to swing downwardly by their own weight to the position shown in Fig. 6. As the display panel 15 is then moved downwardly, the extended arm 45 holds the lower portion of the display panel 15 forwardly of the border frame 14. As the display panel 15 is lowered, the inclined portions or cam surfaces 43 insure that the pivoted arms 45 move to their extended positions, shown in Fig. 6. As the display panel 15 is lowered, the inclined portion 36 of the track guides 16 operate in conjunction with the guide rollers 40 to move the upper portion of the display panel 15 forwardly from the border frame 14. As the rollers 40 enter the vertical part of the guide tracks 16, forward motion of the display panel 15 is stopped and the display panel 15 thereafter moves vertically downwardly to the service position, as shown in dotted lines in Fig. 3.

When the display panel 15 is moved upwardly from the service position, as shown in dotted lines in Fig. 3, to the display position, the upper portion of the display panel 15 is guided vertically by the straight section of the guide tracks 16 and the lower portion is also guided vertically by the guide rollers 44 operating in the guide tracks 17. The weight of the guide rollers 44 and the pivoted arms 45 are such as to maintain the pivoted arms 45 in extended position, as shown in Fig. 6. Just before the display panel 15 reaches the display position, the guide rollers

44 enter the inclined portions 36 of the guide tracks 16 to move the upper portion of the display panel 15 rearwardly toward the border frame 14 and at this time the inclined surfaces or cam surfaces 43 engage the rollers 44 to swing the arms 45 upwardly toward the position shown in Fig. 5 whereby the lower portion of the display panel 15 also moves rearwardly toward the border frame 14. When the display panel 15 reaches the display position it abuts the surfaces 21 of the border frame 14 and may be latched in place by the latch member 48.

The guide rollers and guide tracks of this invention, therefore, provide a ready means for guiding the movement of the display panel with respect to the border frame with the least amount of friction.

While for purposes of this disclosure one form of this invention has been illustrated, other forms thereof may become apparent to those skilled in the art and, therefore, this invention is to be limited only by the scope of the appended claims.

I claim as my invention:

1. A poster panel comprising, a supporting structure including a border frame, a movable display panel for engaging the front surface of the border frame, a vertically arranged guide track carried by the supporting structure and terminating in an inclined portion, a guide roller carried by the display panel and cooperating with the guide track for guiding the display panel as it is moved between a raised display position and a lowered service position, the inclined portion of the guide track moving the display panel against the front surface of the border frame in display position and moving the display panel forward of the border frame when it is lowered to the service position.

2. A poster panel comprising, a supporting structure including a border frame, a movable display panel, a vertically arranged guide track carried by the supporting structure and terminating in an inclined portion at its upper end, a guide roller carried by an upper portion of the display panel and cooperating with the guide track for guiding the upper portion of the display panel as it is moved between a raised display position and a lowered service position, a vertically arranged guide track carried by the movable display panel and having an inclined portion at its lower end, a guide roller carried by a lower portion of said supporting structure cooperating with said last mentioned guide track for guiding the lower portion of the display panel as it is moved between a raised display position and a lowered service position, the inclined portions of the guide tracks moving the display panel against the border frame in display position and moving the display panel forward of the border frame when it is lowered to the service position.

3. A poster panel comprising, a supporting structure including a border frame, a movable display panel structure for engaging the front surface of the border frame, a guide track carried by one of the structures and terminating in an inclined portion, a guide roller carried by the other structure and cooperating with the guide track for guiding the display panel structure as it is moved between a raised display position and a lowered service position, the inclined portion of the guide track moving the display panel structure against the front surface of the border frame in display position and moving the display panel structure forward of the border frame when it is lowered to the service position.

4. A poster panel comprising, a supporting structure including a border frame, a movable display panel for engaging the front surface of the border frame, and guide means carried by the supporting structure and the display panel including upper and lower guide rollers and guide tracks having upper and lower inclined portions for guiding the display panel as it is moved between a raised display position and a lowered service position, the inclined portions of the guide tracks moving the display panel against the front surface of the border frame in display position and moving the display panel forward of the border frame when it is lowered to the service position.

5. A poster panel comprising, a supporting structure including a border frame, a movable display panel structure, a guide track carried by one of the structures and having a cam surface, a guide roller cooperating with the guide track for guiding the display panel structure when it is moved between a raised display position and a lowered service position, a pivoted arm carried by the other structure and carrying said guide roller, the pivoted arm being extended when the display panel structure is lowered to the service position to move the display panel structure forward of the border frame and being retracted by the cam surface when the display panel structure is raised to the display position to move the display panel structure against the border frame.

6. A poster panel comprising, a supporting structure including a border frame, a movable display panel, a vertically arranged guide track carried by the supporting structure and terminating in an inclined portion at its upper end, a guide roller carried by an upper portion of the display panel and cooperating with the guide track for guiding the upper portion of the display panel as it is moved between a raised display position and a lowered service position, a vertically arranged guide track carried by the movable display panel and having a cam surface at its lower end, a guide roller cooperating with the last mentioned guide track for guiding the lower portion of the display panel as it is moved between the raised display position and the lowered service position, a pivoted arm carried by a lower portion of the supporting structure and carrying said last mentioned guide roller and extended and retracted by the cam surface, the inclined portion of the first mentioned guide track and the cam surface of the second mentioned guide track moving the display panel against the border frame in display position and moving the display panel forward of the border frame when it is lowered to the service position.

7. A poster panel comprising, a supporting structure including a border frame, a movable display panel structure for engaging the front surface of the border frame, a guide track carried by one of the structures and terminating in an inclined portion, a guide roller carried by the

other structure and cooperating with the guide track for guiding the display panel structure as it is moved between a raised display position and a lowered service position, the inclined portion of the guide track moving the display panel structure against the front surface of the border frame in display position and moving the display panel structure forward of the border frame when it is lowered to the service position, a counterweight guided by the supporting structure, and a cable connection between the counterweight and the movable display panel structure for balancing the same.

8. A poster panel comprising, a supporting structure including a border frame, a movable display panel for engaging the front surface of the border frame, and guide means carried by the supporting structure and the display panel including upper and lower guide rollers and guide tracks having upper and lower inclined portions for guiding the display panel as it is moved between a raised display position and a lowered service position, the inclined portions of the guide tracks moving the display panel against the front surface of the border frame in display position and moving the display panel forward of the border frame when it is lowered to the service position, a counterweight guided by the supporting structure, and a cable connection between the counterweight and the movable display panel for balancing the same.

9. A poster panel comprising, a supporting structure including a border frame, a movable display panel structure for engaging the front surface of the border frame, a double channel guide track carried by one of the structures and terminating in an inclined portion, a guide roller carried by the other structure and operating in the double channel guide track for guiding the display panel structure as it is moved between a raised display position and a lowered service position, the inclined portion of the guide track moving the display panel structure against the front surface of the border frame in display position and moving the display panel structure forward of the border frame when it is lowered to the service position.
